UNITED STATES PATENT OFFICE.

EDWARD H. McFARLAND, OF CINCINNATI, OHIO, ASSIGNOR TO GENERAL ELECTRIC COMPANY, A CORPORATION OF NEW YORK.

APPARATUS FOR PRODUCING SULFURIC ACID.

1,112,424.

Specification of Letters Patent. Patented Sept. 29, 1914.

Application filed May 10, 1913. Serial No. 766,746.

To all whom it may concern.

Be it known that I, EDWARD H. McFARLAND, a citizen of the United States, residing at Cincinnati, county of Hamilton, State of Ohio, have invented certain new and useful Improvements in Apparatus for Producing Sulfuric Acid, of which the following is a specification.

My invention relates to apparatus used for producing sulfuric acid from smelter fumes containing sulfur dioxid. In what is known as the lead chamber process of producing sulfuric acid from the smoke and fumes given off by copper smelting furnaces, the gases are conducted through large lead-lined chambers in which they are treated with steam in the presence of nitrogen peroxid, the latter being reduced to nitric acid and the sulfuric acid collecting in the bottom of the chamber. The nitrous gases are drawn off from the chamber and subjected to further treatment to recover the nitrogen oxids. Heretofore the movement of the gases has been effected by blowers which operate directly thereon to force them into the lead-lined chamber. This arrangement necessitates lining the chamber of the blower with lead to protect the same from the action of the gases, and for the same reason the rotating part of the blower should be similarly protected. This obviously increases the cost of the apparatus. Furthermore practice has demonstrated that the dust accumulations from the furnace choke up the blades of the blower, the latter being located between the furnace and the acid house. Another and very great objection is the difficulty of determining whether the speed of the blower is proper except after each twelve hours' run when the production is totaled.

I have invented or discovered an arrangement whereby the proper movement of the gases through the system can be accomplished by a centrifugal blower or compressor without subjecting it to the destructive action of the gases, which blower or compressor is arranged to automatically maintain the proper rate of flow of said gases.

I attain these highly desirable results by arranging the compressor or blower to act by induction upon the column of gases flowing from the last chamber of the system, the slight vacuum produced serving to suck the

fumes through the chambers, while the jet of air from said blower or compressor, after creating said vacuum, acts to expel the excess uncombined fumes of sulfuric acid, sulfur-dioxid and nitrogen dioxid. In this arrangement none of the gases pass through the blower or compressor and hence the need for lead coverings is entirely obviated. Furthermore since the gases do not pass through the blower or compressor the dust carried along with the gases has no effect on the blades thereof.

In order to insure the proper speed of the blower or compressor, and vary it with the volume of gases passing through the apparatus, so that the rate of output of the gases will be constant, as is necessary to produce the best results, I place in the exit pipe of the lead chamber a lead covered float, riding on the column of gases therein. The movement of this float is utilized to control the motor which drives the blower. For example, I may use a direct current electric motor and arrange the float to vary the field strength of said motor in order to vary its impeller speed in accordance with the volume of gas passing at any given instant.

The accompanying drawing is a diagram illustrating one of the embodiments of my invention.

The last chamber of the apparatus is indicated at 1 with its exit pipe 2 leading to a stack 3. Entering said stack which is an extension of the pipe is a nozzle 4 which is capable of longitudinal adjustment and cooperates with a tapering section 5 of the stack, so that the effect of said nozzle as a jet ejector can be regulated. A centrifugal blower or compressor 6 of any desired construction is arranged to deliver air into said nozzle to create a draft up through the stack. The blower is driven by an electric motor 7, here shown as a shunt wound direct current motor taking current from supply mains 8. In the field circuit of this motor is a rheostat 9, whose switch arm 10 is connected by a rod 11 to a lever 12 fulcrumed on a stationary support 13 and carrying an adjustable counterweight 14. Pivoted to this lever is a rod 15 which passes down into an upright portion of the exit pipe, and carries at its lower end a disk float 16 exposed to the column of gas coming

from the chamber 1. The exit pipe has a conical enlargement 17 at this point, co-operating with the disk float so that said float operates to enlarge or diminish the annular passage around its periphery as it rises and falls in the exit pipe. The float tends to vary its position in accordance with the speed of the gases passing by it. If the speed, and consequently the volume of gas increases, the float will be lifted to open the exit. This movement tends to cut out some of the resistance from the field circuit and slow down the driving motor, so that the draft will be lessened and the volume of gas will be cut down to normal again. In this way, therefore, the output of the apparatus is maintained at a normal figure and the blower is protected from all injurious influences.

In accordance with the provision of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination with the lead chamber of a sulfuric acid apparatus, of a blower for producing a draft through said chamber, and a device responsive to variations in the volume of gas passing out of said chamber and controlling the speed of said blower.

2. The combination with the lead chamber of a sulfuric acid apparatus, of an ejector nozzle for producing a draft through said chamber, a blower delivering air to said nozzle, a motor for driving said blower, and a device responsive to variations in the volume of gas passing out of said chamber and controlling the speed of said motor.

3. The combination with the lead chamber of a sulfuric acid apparatus, of an ejector nozzle for producing a draft through said chamber, a centrifugal blower delivering air to said nozzle, an electric motor for driving said blower, and a device responsive to variations of the volume of gas passing out of

said chamber and controlling the supply of current for said motor.

4. The combination with the lead chamber of a sulfuric acid apparatus, of an exit pipe from said chamber having a conical engagement, a disk float located in said enlargement, a blower, a nozzle delivering air from said blower to induce a draft through said exit pipe, a motor for driving said blower, and means connected to said float for controlling the supply of energy to said motor.

5. The combination with the lead chamber of a sulfuric acid apparatus, of an exit pipe therefrom, a stack connected with said exit pipe, a nozzle entering said stack, a blower delivering air to said nozzle to suck gases from said chamber through said exit pipe and expel them through said stack, a motor for driving said blower, and a float riding upon the column of gases in said exit pipe and serving to regulate the speed of said motor.

6. The combination with the lead chamber and stack of a sulfuric acid apparatus, of a nozzle in the stack, a blower which discharges air into the nozzle and creates an outward draft in the stack and the chamber, a motor for driving the blower, and means responsive to variations in the volume of gas flowing from the chamber for controlling the amount of air delivered by the blower.

7. In combination the lead chamber of a sulfuric acid apparatus, a pipe, one end of which is connected to the chamber, the other being open to atmosphere, a nozzle that extends into the pipe beyond the chamber and discharges air toward said open end, a rotary blower that delivers air to the nozzle for creating an outward draft in said pipe, a motor for driving the blower, and a means for varying the speed of the motor in accordance with the rate of flow of the gases from the chamber to the pipe.

In witness whereof, I have hereunto set my hand this seventh day of May, 1913.

EDWARD H. McFARLAND.

Witnesses:

W. S. CULVER,
H. A. KNOWLTON.

It is hereby certified that in Letters Patent No. 1,119,424, granted September 29, 1914, upon the application of Edward H. McFarland, of Cincinnati, Ohio, for an improvement in "Apparatus for Producing Sulfuric Acid," an error appears in the printed specification requiring correction as follows: Page 2, lines 56-57, for the word "engagement" read *enlargement*; and that the said Letters Patent should be read with this correction therein that the same may conform to the record of the case in the Patent Office.

Signed and sealed this 10th day of November, A. D., 1914.

[SEAL.]

R. F. WHITEHEAD,

Acting Commissioner of Patents.
